UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

FOLDING-ROLLERS.

1,318,337.

Specification of Letters Patent.

Patented Oct. 7, 1919.

Substitute for application Serial No. 773,919, filed June 16, 1913. This application filed January 31, 1919. Serial No. 274,219.

To all whom it may concern:

Be it known that I, HENRY A. WISE WOOD, a citizen of the United States, residing at New York, in the county of New York and State of New York, have invented new and useful Folding-Rollers, of which the following is a specification.

This case is substituted for my application for patent Serial No. 773,919, originally filed 10 June 16, 1913.

The principal objects of this invention are to provide means whereby the folding rolls of a rotary folding mechanism can grip the sheet to be folded without pressing it between two metallic surfaces, whereby the smearing of the interior sheets will be avoided and yet the rolls can secure a good grip on the sheets. The invention involves improvements in the construction of the rolls.

Reference is to be had to the accompanying drawings in which;

Figure 1 is an end view of a folding cylinder with folding rolls thereon constructed in accordance with this invention;

25 Fig. 2 is a plan of one of these rolls;

Fig. 3 is a sectional view of a portion of the rolls on the line 3-3 of Fig. 1 on enlarged scale; and

Fig. 4 is a transverse sectional view of the 30 same.

As is well known, folding rolls usually employed cause a great deal of smut because they have to bite hard on a sheet to hold it and thus they press its freshly inked interior surfaces together. This frequently causes one sheet to smear the other. This has been a point of considerable difficulty because the sheets must be given a good grip to prevent their slipping back and to cause them to be delivered in exact time with the mechanism. Yet if the sheets are pressed hard at any point except at the margins the smearing above mentioned is likely to occur.

This invention is shown as applied in connection with a folding cylinder 10 having the usual folding blade 11. In order to overcome the above mentioned difficulties, the two folding rollers 12 and 13 are provided with surface flutings.

50 In the form shown the surfaces of the

two rollers 12 and 13 are provided with longitudinal flutings 14 and circumferential flutings 15. This results in the formation of rows of teeth 16, the outer surfaces 17 of which lie in a cylindrical surface. The two rolls are so set up that the projections or teeth of one register with the indentations or depressions of the other, as indicated in Figs. 1, 3 and 4. In this way it will be seen that the sheet is always supported between two points or lines on one side and engaged substantially midway between them by a tooth or projection on the other side. Thus the sheet is gripped with sufficient firmness to cause it to be passed through the rolls accurately and properly and to be deposited in the delivery belts (not shown) squarely and accurately. Yet at no point is the sheet gripped between two metallic surfaces. Consequently the offset and smut are substantially avoided.

Although I have illustrated and described only one form of the invention, I am aware of the fact that modifications can be made therein and that the projections and depressions can be arranged in many forms on the surfaces of the rolls without departing from the scope of the invention as expressed in the claims.

Therefore, I do not wish to be limited in these respects, but what I do claim is:

1. The combination in a folding mechanism, of a pair of folding rolls having their cylindrical surfaces provided with longitudinal and circumferential grooves, thus providing rows of square flat-topped projections, said rolls being arranged to have the projections of each one register with grooves of the other.

2. In a folding mechanism, the combination of a pair of folding rolls having their cylindrical surfaces provided with crossing grooves, whereby a plurality of rows of flat-topped projections are provided, said rolls being arranged so that the projections of each one register with the grooves of the other.

In testimony whereof I have hereunto affixed my signature.

HENRY A. WISE WOOD.
